PRINTING MACHINE

Tom Taylor, Bristol, England, assignor to The Thrissell Engineering Company, Limited, Bristol, England

Application June 7, 1937, Serial No. 146,953
In Great Britain June 12, 1936

10 Claims. (Cl. 101—302)

This invention is for improvements in or relating to printing machines of the kind having a forme movable into and out of engagement with a platen and inking mechanism comprising an ink container, an ink distributor, means to transfer ink from the container to the distributor, inking means to transfer ink from the distributor to a forme, and rolling means disposed between the means to transfer ink from the container and the inking means to roll the ink on the surface of the distributor.

In printing machines of the type described it has previously been proposed to apply ink to a flat surface on which the ink was rolled and from which the ink was transferred to the forme. Machines constructed in accordance with these proposals usually occupy a comparatively large amount of space.

The term "rough ink" when used herein and in the appended claims means ink which is contained in the ink container or which has been removed therefrom but which has not been rolled so as to make it suitable for application to the inking means.

According to the invention there is provided inking mechanism of the type described wherein the ink distributor comprises a curved surface arranged to reciprocate between the transfer means and the inking means in a manner such that the rolling means engages the curved surface during the movement of the latter in each direction for the purpose of spreading the ink over the curved surface. The extent of reciprocation of the curved surface is regulated in a manner such that that portion of the curved surface to which ink is transferred by the transfer means is not engaged by the inking means in order that the inking means shall not receive ink from that portion of the curved surface to which "rough" ink is applied by the transfer means.

The curved surface may be rotatable about an axis coincident with the centre of curvature of the surface and the curved surface may comprise an arc of a circle.

The inking means may be carried by a support movable in an arcuate path, and the inking means arranged to be movable relatively to the support to permit the required engagement between the inking means and a forme.

The relative movement between the support and the inking means may be provided by slidably mounting the inking means on the support and controlling said means by a resilient element or elements, which is or are operative when the inking means is in engagement with a forme,

to permit the inking means to move radially away from the point about which the support moves so that the inking means may move over and engage the surface of the forme.

One way of carrying the invention into effect will be described by way of example with reference to the accompanying drawings in which:

Figure 1 is a side elevation, partly in section, of a printing press with the forme in the upper position.

10

Figure 2 is a side elevation, partly in section, showing certain of the parts shown in Figure 1 in different positions from the positions in which they are shown in Figure 1.

10

Figures 3 and 4 show diagrammatically the manner in which ink is spread over the surface of a distributor.

Like references refer to like parts throughout the specification and drawings.

Referring to the drawings, the forme 3 of the printing machine is carried by a head 4 which is pivoted at 5 so as to be oscillatable towards and away from the platen 6 which is positioned on the bed 7 of the machine. The printing head is oscillated by means of crank and toggle mechanism, comprising two links 8 and 8a, the former being pivoted at 9 to the bed 7 of the machine, and the latter connected at 10 with the head 4 of the machine by a projection 11. A link 12 is connected with the arms 8 and 8a at 13 and is also connected with a crank 14 which is driven from the main drive of the machine.

20

25

30

To the printing head 4 there is connected the inking mechanism which comprises an ink container 15 and a curved distributing surface 16 which may comprise a cylindrical roller but which is shown in the drawings as an arc of a circle. The distributing surface is mounted for rotation with a shaft 17, the axis of rotation of which is coincident with the centre of curvature 40 of the curved surface 16.

35

A toothed sector 18 is connected to the distributing surface 16 and engages with a further toothed sector 19 which is connected with inking means shown as rollers 20. The inking rollers 20 are carried by a support 21 and are arranged to be movable relatively to the support 21 by reason of the fact that the rollers 20 are carried on frames 22 which are secured to rods 23 slidably in the support 21 and controlled by springs 24. The support 21 is arranged to move in an arcuate path about a spindle 25 and the springs 24 control the inking rollers 20 so that as the support 21 moves through its arcuate path and the inking rollers 20 engage with the forme 50 55

3 to apply ink thereto, the inking rollers move relatively to the support in a direction which is radial to the axis of the spindle 25 about which the support 21 is moved.

5 The ink in the ink duct 15 is transferred from the duct to the surface of the distributor 16 by a vibrator or messenger roller 26 which is arranged to oscillate between a roller 27 which engages with the ink in the duct 15 and the surface of the distributor 16 as can be seen from Figure 1. The roller 27 is rotated whilst the messenger roller 26 is in engagement therewith by means of a ratchet wheel 28 with which a pawl 29 mounted on an arm 30 co-operates, the arm 30 being connected by a link 31 to the sector 18 which operates the distributor 16.

A plurality of freely rotatable rollers 32 are positioned adjacent the surface of the distributor 16, and are arranged to roll over the surface of 20 the distributor the ink deposited upon the surface 16 by the messenger roller 26. As will be seen from the drawings, the rollers 32 are disposed between the transfer roller 26 and the inking means 20.

25 The distributing surface 16 is arranged to oscillate about the axis of the shaft 17 and so transfer the ink which has been rolled over the distributor surface by the rollers 32 to the inking rollers 20.

30 As will be seen from Figure 2, the inking rollers 20 are arranged to be in position to receive ink from the distributor surface 16 whilst the forme 3 is co-operating with the platen 6.

It will be seen, therefore, that the distributing 35 surface 16 is movable between the transfer means 26 and the inking rollers 20 and in timed relationship with the inking rollers and the arrangement is such that the rough ink on the curved surface of the distributor 16 is engaged only by 40 the rollers 32 during the movement of the distributor in each direction. In this manner some at least of the ink which is on the distributing surface is rolled over the surface of the distributor 16 at least twice before it is transferred 45 to the inking rollers 20, and it is possible to obtain a more even film of ink on the distributing surface 16 than is the case when the distributing surface is moved in one direction only.

Figures 3 and 4 show the distributing surface 50 in its extreme positions, and as can be seen from these figures, the ink transferred to the distributing surface 16 is spread over only a relatively small area of the surface 16, the distance along the arc formed by the surface 16 being indicated 55 by the distance S shown in Figures 3 and 4. The ink transferred to the surface 16 along the distance S is rough ink and the rollers 32 roll the ink so that it is relatively smooth over the remainder of the surface 16. From Figures 3 and 60 4 it will be seen that the extent of the movement of the curved surface 16 in the direction of the inking rollers 20 is such that the inking rollers 20 do not engage with that part of the curved surface 16 to which rough ink is applied.

65 The operation of the inking rollers 20 and the distributing surface 16 is effected in timed relationship with the movement of the forme 3 due to the fact that the spindle 25 previously referred to, and about which the support 21 moves, 70 is connected with the head 4 of the printing press. The support 21 is formed as a bell crank lever, one arm of which supports the inking rollers 20, the other arm being connected with a link 33 pivoted at 34 to the bed 1 of the machine.

75 The sector 19 also is connected to the spindle

25 so that as the printing head 4 is moved the support 21 is correspondingly moved and the sector 19 by co-operation with the sector 18 causes the distributor 16 to be rotated about the axis of the shaft 17, and this movement in turn is 5 transmitted through the link 31 to the pawl 29 which operates the ratchet 28 and rotates the roller 27. It will be seen, therefore, that the roller 27 of the inking mechanism is movable in timed relationship with the movement of the 10 printing head.

A cam (not shown) is connected with the spindle 25 and is arranged to operate the messenger roller 26 so that it transfers ink from the roller 27 to the distributor surface 16 at the required 15 intervals.

What I claim as my invention and desire to secure by Letters Patent is:—

1. In ink applying mechanism for printing machines, the combination with a source of supply 20 of ink, of an ink distributor having a distributing surface, transfer means for supplying rough ink from said source to a portion only of said surface, inking means receiving ink from said surface, and means for moving said distributor 25 to cause the distributing surface thereof to engage and move over said inking means, the extent of such movement being insufficient to engage that portion of the said surface to which rough ink is supplied. 30

2. In ink applying mechanism for printing machines, the combination with a source of supply of ink, of an ink distributor having a distributing surface, transfer means for supplying rough ink from said source to a portion only of said surface, inking means receiving ink from said surface, means for moving said distributor to cause the distributing surface thereof to engage and move over said inking means, the extent of such movement being insufficient to engage that portion of the said surface to which rough ink is supplied, and means cooperating with said distributing surface for spreading the ink thereover. 35

3. In ink applying mechanism for printing machines, the combination with a source of supply 45 of ink, of an ink distributor having a distributing surface, transfer means for supplying rough ink from said source to a portion only of said surface, inking means receiving ink from said surface, means for moving said distributor to cause the distributing surface thereof to engage and move over said inking means, the extent of such movement being insufficient to engage that portion of the said surface to which rough ink is supplied, and roller means positioned adjacent 55 the path of movement of said distributing means and engaging the surface thereof to spread the ink over said surface.

4. In ink applying mechanism for printing machines, the combination with a source of supply 60 of ink, of an ink distributor having a curved distributing surface, transfer means for supplying rough ink from said source to a portion only of said surface, inking means receiving ink from said surface, and means for imparting oscillatory movement to said distributor to cause the distributing surface thereof to engage and move over said inking means, the extent of such movement being insufficient to engage that portion of the said surface to which rough ink is supplied. 65

5. In ink applying mechanism for printing machines, the combination with a source of supply of ink, of an ink distributor having a curved distributing surface, transfer means for supplying rough ink from said source to a portion only of 70

5 said surface, inking means receiving ink from said surface, means for imparting oscillatory movement to said distributor to cause the distributing surface thereof to engage and move over said inking means, the extent of such movement being insufficient to engage that portion of the said surface to which rough ink is supplied, and means cooperating with said distributing surface for spreading the ink thereover.

10 6. In ink applying mechanism for printing machines, the combination with a source of supply of ink, of an ink distributor having a curved distributing surface, transfer means for supplying rough ink from said source to a portion only 10
15 of said surface, inking means receiving ink from said surface, means for imparting oscillatory movement to said distributor to cause the distributing surface thereof to engage and move over said inking means, the extent of such movement being insufficient to engage that portion of the said surface to which rough ink is supplied, and roller means positioned adjacent the path of movement of said distributing means and engaging the surface thereof to spread the ink 25 over said surface.

15 7. In ink applying mechanism for printing presses of the type provided with cooperating, relatively movable form and platen members, the combination with a source of supply of ink, 20
20 of an ink distributor having a distributing surface, transfer means for supplying rough ink from said source to a portion only of said surface, inking means receiving ink from said surface, said inking means being supported for 25
25 movement into engagement with and over the active face of said form to apply ink thereto, and means for moving said distributor to cause the distributing surface thereof to engage and move over said inking means while the latter is out 30
30 of engagement with said form, the extent of such movement being insufficient to engage that portion of the said surface to which rough ink is supplied.

35 8. In ink applying mechanism for printing presses of the type provided with cooperating, relatively movable form and platen members, the combination with a source of supply of ink, 35
40 of an ink distributor having a distributing surface, transfer means for supplying rough ink from said source to a portion only of said surface, inking means receiving ink from said sur- 40
45 face, said inking means being supported for 45
50

5 face, said inking means being supported for movement into engagement with and over the active face of said form to apply ink thereto, and means for moving said distributor to cause the distributing surface thereof to engage and move over said inking means while the latter is out of engagement with said form, the extent of such movement being insufficient to engage that portion of the said surface to which rough ink is supplied, said inking means including ink receiving rollers and means yieldingly urging said rollers into engagement with said form and said distributing surface.

10 9. In ink applying mechanism for printing presses of the type provided with cooperating, 15 relatively movable form and platen members, the combination with a source of supply of ink, of an ink distributor having a curved distributing surface, transfer means for supplying rough ink from said source to a portion only of said surface, inking means receiving ink from said surface, said inking means being supported for movement into engagement with and over the active face of said form to apply ink thereto, means for imparting oscillatory movement to said distributor to cause the distributing surface thereof to engage and move over said inking means while the latter is out of engagement with said form, the extent of such movement being insufficient to engage that portion of the said surface to which rough ink is supplied, and means cooperating with said distributing surface for spreading the ink thereover.

20 10. In ink applying mechanism for printing machines, the combination with a source of supply of ink, of an ink distributor having a generally cylindrical distributing surface, transfer means for supplying rough ink from said source to a portion only of said surface, inking means receiving ink from said surface, rollers supported 25
25 for engagement with said surface to spread the ink thereover, and means for oscillating said distributor about the axis of said surface to cause the latter to move over said inking means and said spreading rollers, the range of movement 30
30 of said distributor being insufficient to contact said inking means with the said portion of said surface supplied with rough ink, said spreading rollers being disposed intermediate said inking means and said transfer means.
